[57] CLAIM

The ornamental design for an automobile, as shown and described.

DESCRIPTION

FIG. 1 is a front and left side perspective view of an automobile showing my new design;

FIG. 2 is a rear and left side perspective view thereof; FIGS. 3 and 4 are, respectively, front and rear perspective views thereof; and,

FIG. 5 is a left side elevational view thereof.

The right side, not shown, is the mirror image of the left side.

The top of the automobile is understood to be plain and unornamented.

FIG. 1

FIG. 2

FIG. 3

FIG. 4

FIG. 5
